PAINT CAN HOLDER

William Schroeder, Bergenfield, N. J.

Application February 7, 1949, Serial No. 725

Term of patent 14 years

(Cl. D17—12)

To all whom it may concern:

Be it known that I, William Schroeder, a citizen of the United States, residing at Bergenfield, New Jersey, have invented a new, original, and ornamental Design for a Paint Can Holder, of which the following is a specification, reference being had to the accompanying drawings, forming part thereof, in which:

Figure 1 is a front elevational view of a paint can holder, showing my new design;

Figure 2 is a side elevational view of the paint can holder shown in Figure 1;

Figure 3 is a rear elevational view of the paint can holder shown in Figure 1; and

Figure 4 is a cross-sectional view of the paint can holder shown in Figure 3, the same having been taken substantially along the line 4—4 thereof, looking in the direction of the arrows.

I claim:

The ornamental design for a paint can holder, as shown.

WILLIAM SCHROEDER.
